FILTER AND CLEANOUT MECHANISM
FOR FLUES AND STACKS

Charles D. Wright, San Francisco, Calif.

Application November 13, 1951, Serial No. 256,024

4 Claims. (Cl. 183—66)

1

This invention relates to apparatus and methods for cleaning out stacks, chimneys or flues of furnaces or incinerators, and is particularly directed to a mechanism for automatically removing cinders and other heavier products of combustion from a receptacle in which such products have been deposited.

The present apparatus is an improvement over the disclosure of my prior Patent No. 1,462,728, issued July 24, 1923 for a Spark Arrestor. In said patent, means were provided for incorporation with a stack or flue whereby cinders, sparks, and the like were prevented from being discharged through the flue with the lighter smoke, and whereby such arrested cinders, sparks and the like were deposited in a receptacle from which they could be periodically manually removed. Although this type of arrester constituted an advance over the prior art mechanisms, certain shortcomings were present which I have eliminated by means of the presently to be described structure. One of the chief difficulties encountered in my prior apparatus was the cleaning of the receptacle into which the heavier products of combustion were supposed to be deposited. As will be understood, the arrested products would have to be manually removed from the receptacle approximately every day. Not only is this a tedious and time-consuming chore, but it requires a complete shut-down of the operation of the furnace or incinerator. I also found that in many instances, all of the heavier combustion products would not be deposited in the receptacle, but would fall to the bottom of the main flue or otherwise be trapped between the flue and receptacle.

It is therefore an object of the present invention to provide apparatus for use with a flue having a spark arrester therein, whereby the sparks, cinders, and heavier products of combustion may be simply and conveniently removed without requiring manual handling thereof.

Another object of this invention is to provide apparatus of the type described which may be selectively placed into or out of operation without affecting the normal operation of the furnace or incinerator, and without requiring shutting down of the latter.

A further object of my invention is to provide apparatus of the above character in which portions of the flue structure other than the refuse receptacle may be periodically cleaned of the heavier products of combustion which may be disposed therein in a simple and convenient manner.

2

A still further object of this invention is to provide a method for efficiently and systematically disposing of cinders and other heavier products of combustion from a flue section and a refuse receptacle associated therewith.

The invention possesses other objects and features of advantage, some of which, with the foregoing, will be set forth in the following description of the invention which is illustrated in the drawing accompanying and forming part of the specification. It will be understood that the invention is not to be limited to the exemplary apparatus or the specific procedure herein shown and described, as variations thereof may be employed which come within the scope of the appended claims.

Referring to said drawing:

Figure 1 is a vertical cross-sectional view of the apparatus of the present invention.

Figure 2 is a cross-sectional view taken substantially in the plane indicated by the line 2—2 of Figure 1.

Figure 3 is a sectional view taken substantially in the plane indicated by the line 3—3 of Figure 1.

In conventional installations, a generally vertical stack or flue 6 is provided on a furnace or incinerator, not shown, so as to carry away the products of combustion. While it is preferable to only have smoke pass through the stack, it is virtually impossible to control or regulate combustion to the extent that cinders, sparks or the like will not pass upwardly through the stack with the smoke thereby creating fire hazard as well as causing the deposit of such refuse on adjoining buildings and streets. To prevent the heavier combustion products from being discharged into the atmosphere, a baffle and screen arrangement is provided which will permit the smoke to pass therethrough, but which will effectively trap the cinders, sparks, etc. As here shown, the upper end of the stack 6 is connected to one arm of a T section 7, the other arm of the latter being connected to an axially aligned vertical auxiliary stack 8 whose function will be later described. A short horizontally disposed flue section 9 is connected to the leg of section 7, and by means of a damper plate 11 normally positioned as indicated in Figure 1, the products of combustion, upon passing upwardly through stack 6, will be directed toward and into the flue section 9.

Secured to the other end of section 9 in spaced relation to stack 6 is a main exhaust flue 12 having a closed bottom 13 and an open top 14

through which the smoke is discharged to the atmosphere. The combustion products passing through section 9 are deflected downwardly by means of a baffle plate 16 which is secured to and extends downwardly from the upper side of the section so that its forward end terminates substantially flush with the end of the section, and spaced above the lower side of the latter a distance approximately one-half the diameter of the section. A screen 17 extends from the end of baffle 16 across the main flue 12. With this construction, it is believed clear that as all of the combustion products are directed under the screen 17, the cinders and heavier elements will be separated from the smoke, and the latter may continue its travel for discharge through the flue end 14 while the heavier elements may either accumulate on the screen and/or gravitally fall to the bottom 13 of the stack 12.

As will be understood, the trapped cinders and heavier products of combustion must be periodically removed, and heretofore, such removal necessitated manual handling of the refuse. In accordance with the teachings of the present invention, such removal may now be accomplished in a rapid automatic manner, without interfering with the continued operation of the furnace. It will be noted that a refuse receptacle 18 is placed immediately adjacent the lower end of flue 12 and is provided with a lateral opening 19 adjacent the bottom thereof which is aligned with an opening 21 adjacent the bottom of the flue. Opposite the opening 19, I provide an opening 20 whose effective area may be controlled by means of a louvre 25 so as to regulate the nature of the combustion products leaving the stack. It should be pointed out that due to the arrangement of parts and more particularly to the downward deflection of the combustion products, the only products passing out from the stack will be so clarified as to be practically invisible to the eye.

As best seen in Figure 2, one wall of the receptacle is provided with a slot or orifice 22 adjacent the bottom 23 thereof, and this slot is preferably on a wall angularly disposed to the wall in which the opening 19 is provided. A tapered housing 24 has a diverging chamber 26 opening into the slot 22, and the chamber is also placed in flow communication with the suction side of a blower 27 by means of a suitable conduit 28. A motor 29 is arranged to drive the blower, and the blower exhaust is connected to a conduit 31 which terminates in a sewer line 32. Intermediate the blower and sewer, I provide a water line 33 equipped with a suitable valve 34, and if desired or required by local ordinances, a trap 36 may likewise be utilized.

From the foregoing description, the operation of the mechanism for drawing the refuse from the lower end of flue 12 and depositing the same in the sewer line should be clear. However, in order to permit the blower to establish proper suction throughout the flue system, the following should be incorporated therein. Referring first to the auxiliary stack 8 and damper 11, it will be seen that the latter is pivotally mounted at the upper juncture of the section 9 and T section 7 so that it may be manually rotated by lever 41 from the position indicated in Figure 1 to a position normally related thereto and completely overlying the inlet to flue section 9. Connected to the damper 11 and movable therewith is a screen 42 which normally is positioned as shown in Figure 1, but which rotates to overlie the opening to auxiliary stack 8 when the damper 11 closes

the flue section 9. In this manner, when the blower is in operation, the operator will close the section 9 with damper 11 and the operation of the furnace may be continued with the screen 42 catching the heavier combustion products. Likewise, in order to establish suction for removal of the refuse, it is necessary to shut off the atmospheric opening at the upper end of stack 8 which is of course effected by the damper 11. 10 With the damper 11 in its closed position overlying flue section 9, a damper plate 43 disposed in main flue 12 above the screen 17 must likewise be closed by means of handle 44 to shut off the atmospheric opening 14. A door 46 overlies 15 an opening in a wall of the flue 12 and is arranged to slide in a pair of channels or rails 47 so that access may be had to the screen 17. By opening the door, the operator may brush the screen as suction is being applied and the door may then 20 be closed or opened a small amount as the cleaning process is continued. The refuse will, for the most part, be disposed at the lower end of flue 12, and to assist in drawing the same into receptacle 18, I provide a plurality of apertures 51 25 in a wall of flue 12 opposite to the opening 20. These apertures are normally covered as by means of a plate 52, but when it is desired to suck the refuse into the receptacle, the plate is raised in suitable rails 53 to uncover the apertures and 30 thus create a draft along the bottom of the flue. After the flue has been substantially emptied of the refuse, plate 52 may be closed, and to complete the evacuation of refuse from receptacle 18, a similar series of apertures 54 which are provided in the receptacle wall opposite to slot 22 are 35 opened by raising a plate 56 in its guide rails 57. This will cause a suction along the bottom of the receptacle and force the refuse through the blower for admixture with water and deposit in the sewer line 32.

When the cleaning operation is completed, the blower is stopped, apertures 51 and 54 covered with their respective plates, damper 43 is opened, and plate 11 is rotated into its normal position 45 closing the auxiliary stack 8. It should be pointed out that the number and size of the respective apertures 51 and 54 will be such so that their combined cross-sectional area will preferably be less than the cross-sectional area of orifice 22. 50 Similarly, the orifice size should be substantially equal to or slightly less than the cross-sectional area of the blower intake conduit 28. In this manner, a positive suction draft along the various portions of the system will be insured, and a 55 simple clean out arrangement is provided which will not interfere with normal operations, yet which will adequately remove the trapped refuse from the flue system without requiring manual handling of the refuse.

60 I claim:

1. Apparatus of the character described comprising, a first flue section through which products of combustion from a furnace and the like are adapted to pass, a second flue section in spaced parallel relation to said first section, duct means interconnecting said sections intermediate the ends thereof, a screen disposed in said second section in the path of the products of combustion entering the section from said duct 65 means, damper means in said first section whereby products of combustion may be selectively directed into said duct means or toward the upper end of said first section, damper means in said second section intermediate the upper end thereof and said screen, said second section having

a refuse discharge opening adjacent the lower end thereof, and suction establishing means in flow communication with said opening for drawing refuse therethrough.

2. Apparatus as set forth in claim 1 in which said second section is provided with an air inlet opening disposed opposite to said discharge opening, and means for selectively opening and closing said air inlet opening.

3. Apparatus of the character described comprising a first flue section having an open top through which products of combustion from a furnace and the like are adapted to pass, a second flue section having an open top and a closed bottom, duct means intermediate said sections intermediate the ends thereof for introducing said combustion products from said first to said second sections, a screen in said second section intermediate said duct means and said open top, a damper in said second section intermediate said screen and open top for selectively opening and closing said second section, said second section further having a refuse discharge opening adjacent said closed bottom, a refuse receptacle having a chamber therein, means establishing flow communication between said chamber and said second section, means in flow communication with one side of said chamber for establishing a suction draft in said receptacle and said second flue section, means on said receptacle and said section respectively for controlling the flow of air therethrough, and damper means associated with said first section for selectively directing all of said combustion products through said duct means or for closing said duct means and directing said products through said open top of said first flue section.

4. Apparatus of the character described comprising: a first flue section having an upper open

end portion through which products of combustion are adapted to pass, a second flue section having an upper open end portion in parallel spaced relation to said first section, conduit means interconnecting said sections intermediate the ends thereof, a perforate member extending across said second section in the path of the products of combustion entering the section from said conduit means, valve means in said first section whereby products of combustion may be selectively directed into said conduit means or toward the upper end of said first section, valve means in said second section intermediate said perforate member and said open end thereof, means defining a refuse discharge opening adjacent the bottom of said second section, and a perforate member disposed in said first section intermediate said first mentioned valve means and the open end of said first section and movable to intercept products of combustion upon movement of said first valve means to close said conduit means.
